G. W. BEARDSLEE.
JACKER FOR PLANING MACHINES.

No. 8,497.

Patented Nov. 4, 1851.

UNITED STATES PATENT OFFICE.

GEORGE W. BEARDSLEE, OF ALBANY, NEW YORK.

PLANING-MACHINE.

Specification of Letters Patent No. 8,497, dated November 4, 1851.

To all whom it may concern:

Be it known that I, GEORGE W. BEARDSLEE, of Albany, in the county of Albany and State of New York, have invented certain new and useful Improvements in Jackers for Planing-Machines; and I do hereby declare the following to be a full, clear, and exact description of the same, reference being had to the accompanying drawings, making part 10 of the same, in which—

Figure 1, represents a side view. Fig. 2, represents the bolt and nut for adjusting, and allowing the front of the cutter to rise and fall with the different thicknesses of 15 boards or plank to be planed. Fig. 3, a sectional top view of the stock and cutter.

Similar letters in the several figures represent like parts.

The nature of my invention consists in the 20 application of springs or weights to each edge and end of cutter stocks on which knives with caps are bolted for the planing of boards or plank whereby they are caused to yield both on the heel and edge.

25 To enable others skilled in the art to make and use my invention I will proceed to describe the same with reference to the drawings.

In the practical use of all continued shaving cutters in power machines for planing boards and plank, the following difficulties have occurred, and have to a great extent rendered them inoperative. By far the larger proportion of lumber that is planed 30 by power machines, has embedded in its surface, sand and other gritty substances, which destroy the keen cutting edge of a series of knives; and also, all lumber before it is planed is of various thicknesses. The first 35 difficulty, my improved cutter stock, to a great extent, obviates in the following manner: I place this stock in advance of a series of stocks which are fixed by any of the known modes upon side plates for the purpose (by a series of cuts) of reducing boards 40 to a uniform thickness. In this position by the action of the springs, the knife stock α , is firmly bolted on the metal bar e , with the bolt and nut o . This being firmly attached,

45 through said bar are passed the bolts r , and n (Figs. 2 and 1,) in a mortise, and by the pin k , are kept from a backward or forward movement, and allowed to rise and fall at the point of the cutting edge to a given 50 height by the slot p . The heel of the stock is held firmly by the spring l , and bolt and

nut n, m . The steel plate t , is firmly bolted to the underside of the stock at the heel, and forms a throat for the next knife, and by the spring l , is firmly held upon the board, while passing through under the cutters. The front edge of the cutter is adjusted by the nut j , working in the socket h , on the bolt r , by which the edge can be fixed to any desired height from the bed, but by the top spring l , and the slot p , is permitted to rise to the inequalities of the boards or plank. This stock is made with a fixed throat like a hand plane, and always takes a given shaving, or one of a given thickness, 55 which is governed by the bar of steel u , which is firmly bolted on the front edge of the stock.

It will readily be perceived that, the double action given by the above described 60 arrangement causes this plane to take the first shaving off the board or plank whether it is thick or thin, or of an unequal thickness, and thereby removes all dirt and gritty substances from the plank or board, before 65 it comes in contact with the cutting edges of the remaining cutters; hence they are protected from the causes which destroy the keenness of their cutting edges; or, in other words, it becomes a "jacker" to every board 70 or plank whether thick or thin.

In the running of lumber of great inequalities of thickness, it will be perceived that this cutter accommodates itself to such 75 inequalities, and forms a self adjustable 80 throat to the next cutter, which takes the unequal shaving from the board or plank.

In the double action of this stock, if the cutting edge of the knife is in the act of removing a shaving from a thin board, and 85 a thick one is approaching it, the bar u that forms the throat to this cutter (it being rounded on the under side for this purpose) is caused to rise by the thick board; it being firmly fixed to the stock, it carries up the 90 cutting edge with it, to the plane of the thick board; but the heel is still held firmly to the thin board until raised by the thick board.

The bolt n , which supports the upper 95 spring, is hinged to the bolt r , by the steel pin q , by which arrangement it is allowed to vibrate with the rocking or oscillating motion given to the stock. By the square part of the bolt r , at the point where the bolt 100 passes up through the mortise in the bar e , they are so fitted and adjusted that both 105 110

ends of the stock rise equally being guided by said bolt.

When this stock and cutter is used for a whole series of cutters, the adjustment to the 5 side plates, is made in the same manner. When used thus all these stocks after the first one would be held to a fixed position by the top springs or weights being applied with greater force. The object of this arrangement is to permit the cutting edge to 10 rise when one board runs under the other. This difficulty is of common occurrence in all machines where the whole power of planing is applied to the feed, and one board pushes the other through between a fixed 15 bed and cutters, as not infrequently boards are wedge-shaped at their ends, or wedges are formed by the separation of boards in cross grained lumber. By permitting the stocks to rise, if the above difficulty occurs, 20 the breaking up of the stocks or bed is prevented. Thus by my improved double elas-

tic stock, by the application of weights or springs, both, to the point on the stock in line with the cutting edge of the knife and also to the heel, this difficulty is effectually removed. 25

Having thus fully described the nature of my invention, what I claim therein as new and desire to secure by Letters Patent is, 30

The application of springs or weights to cutter stocks, both at their point in line with the cutting edge of the knife, and also to the heel, by which a double action is given to the stock both at the heel and edge, allowing 35 it to rise and oscillate to the inequalities of boards or plank, substantially as described and for the purposes, herein set forth.

GEO. W. BEARDSLEE.
